ERNEST L. WOOLLEY, OF PROVIDENCE, RHODE ISLAND.

AUTOMATIC COMBUSTION-CONTROLLING DEVICE.

Application filed November 4, 1924. Serial No. 747,802.

This invention relates to an improved automatic control-device for regulating combustion in steam-boiler furnaces.

The principal object of the invention is to provide an apparatus of the type specified which is extremely sensitive and instantly responsive to variations in steam pressure and steam flow to regulate combustion in accordance with requirements with minimum consumption of fuel.

A particular object of the invention is to provide a combustion-controlling device which is influenced by the factors of both steam pressure and steam flow to respond more quickly to changing conditions of steam generation and steam consumption, whereby to prevent loss of pressure in the boiler without increasing combustion to a wasteful degree.

Another object of the invention is to provide a control-device which may be employed to regulate the fuel supply, the induced and forced draft in the furnace and other controls if required.

Further objects of the improvement are set forth in the following specification which describes a preferred embodiment of the invention as illustrated in the accompanying drawings. In the drawings:

Fig. 1 is a general view of a steam-boiler furnace of conventional type showing my improved control-device as applied to use therewith for regulating the fuel supply from an automatic stoker and also for controlling the forced and induced draft therein;

Fig. 2 is a vertical sectional view of the control-device;

Fig. 3 is a fragmentary sectional view illustrating a modified form of one of the control-elements of the apparatus;

Fig. 4 is a plan view of the control-device shown with its casing in section to illustrate the operating parts therein;

Fig. 5 is an enlarged detailed view of the differential-weight compensating-mechanism which connects two of the control-elements of the apparatus;

Fig. 6 is a plan view of the same;

Fig. 7 is a still further enlarged view showing a detail of the construction of the differential-weight mechanism;

Fig. 8 is an enlarged longitudinal sectional view of the main steam pipe leading from the boiler, illustrating a usual form of

Pitot tube which may be used as the steam flow element of the control;

Fig. 9 is a cross-sectional view of the main steam pipe showing the Pitot tube; and

Fig. 10 is a longitudinal sectional view of the main steam pipe showing an orifice plate applied thereto as an alternative form of flow-control element.

Referring to the drawings, my improved control-device comprises a plurality of co-ordinated mechanisms which will first be described in detail as separate units. The several units of the apparatus are preferably enclosed in a casing C herein illustrated as a rectangular box supported from a flanged base c and provided on the front with an opening or door d.

Motor.—The motor or actuator M which furnishes the power for operating the furnace controls may be of any suitable type, and I have herein illustrated a fluid-pressure cylinder 2 containing a sliding piston 4 which may be operated by compressed air, oil or steam-pressure taken direct from the boiler. As shown in Fig. 2 the cylinder 2 is lined with a bushing 3, preferably constructed of brass or bronze, within which is the sliding piston 4. The piston-rod 5 slides through a suitable gland or stuffing box 6 at the top of the cylinder 2 and is braced by a bearing on an arm 7 extending from the upper wall of the casing C. As indicated in Fig. 1, the upper end of the piston-rod 5 projects through an opening in the top of the casing C and is connected to the various controls of the furnace, to be later described, by means of chains or cords. In some cases the piston-rod may be extended downwardly through a gland at the bottom of the cylinder 2 to project below the casing C for connection with controls at a lower level, when so required.

At one side of the cylinder 2 is a slide-valve 10 for controlling the admission of pressure through two ports 12 and 13 in the valve-casing or steam-chest 14, the ports communicating with the opposite ends of the cylinder through ducts 15 and 16. It will be noted that the valve-casing 14 is shown in Fig. 4 as being offset to the front of the cylinder 2, but to render the showing of Fig. 1 clearer I have here illustrated it as being in the vertical plane on which the section is taken through the axis of the cylinder.

Valve-gear.—The valve 10 slides in a sleeve or bushing 18 having relatively narrow openings 19 and 20 in its side which communicate respectively with the ports 12 and 13. The valve 10 is controlled by a valve-gear V which operates on the well known principle of the "trick valve" employed quite generally with mechanisms used for reversing marine engines by steam power. The valve-rod 21 extends upwardly through a stuffing-box 22 and at its upper end carries a forked joint 23 by means of which it is pivotally connected at 24 to a rockable lever 25. The lever 25 has a pin-and-slot connection 27 with a slideable piston 26 to be later described. At its opposite end the lever 25 is pivotally connected at 29 to a reach-rod 30 which is joined at its upper end to a second rockable lever 32. The lever 32 is fulcrumed at 33 on a fixed bearing 34 extending from the side of the casing C. The long arm of the lever 32 has a fork at its end formed with slots 35 which are engaged by a cross pin 36 projecting from the sides of a collar 37 fast on the piston-rod 5. The reach-rod 30 is preferably made in two parts which are connected by a turnbuckle 31 to provide for adjusting the length of said rod. It will be obvious that through the above arrangement of the valve-gear V the valve 10 is controlled in position from the sliding action of the piston 26 under the further control of the piston-rod 5 in the cylinder 2.

Static steam pressure cylinder.—The piston 26 is operated under direct steam pressure in a relatively small cylinder 40 constructed in the form of a tube. The pressure cylinder 40 is supported vertically from a step or pedestal 41 secured to the base of the casing C and having a bore into which the tube or cylinder 40 fits. The pedestal 41 is provided with a duct or opening 42 on its side into which is fitted a suitable nipple 43 connecting with the steam supply pipe to be later described. A small hole drilled through the lower end of the cylinder or tube 40 in line with the duct 42 admits steam pressure into the cylinder from the nipple or steam pipe 43.

The piston 26 is enlarged at its lower end and bored to adapt it to enclose the steam cylinder or tube 40 so that the pressure in said cylinder will act to raise the piston in the manner as hereinafter more fully described. At the lower end of the piston 26 is a flange 44 which supports a cylindrical weight 45 surrounding the piston and acting as a counterbalance against the steam pressure in the cylinder. The weight 45 is held from turning on the piston 26 by means of a screw 46, and the weight and piston are prevented from turning by means of a guide-screw 47 inserted through the side of the casing C with its end engaging a slot or

keyway 48 on the side of the weight. It will be seen, therefore, that the piston 26 is moved from the pressure in the cylinder 40 to rock the lever 25 to operate the valve 10 in the manner and for the purpose as hereinafter more fully explained. The steam pressure device P above described constitutes the static pressure control-element of the apparatus and is connected by a differential mechanism to the steam flow control-element of the apparatus which is next described.

Steam flow control-element.—The steam flow control-element of the apparatus consists of a slideable piston 55 controlled in position under pressure from opposite sides of the Pitot tube or orifice plate in the main steam pipe leading from the boiler. The pressure acts through the medium of a quantity of mercury in a mercury pot F, as next described. The mercury pot F consists of a cylindrical casing 50 mounted on a bracket or bearing 51 fastened to the interior of the casing C by means of screws 53. The casing 50 encloses a cylinder 54 in which is the piston 55 having upper and lower piston-rods 56 and 57 sliding through stuffing boxes 58, the upper rod 56 being further supported from a bearing 59 carried by the arm 7 which braces the piston-rod 5. The piston 55 is normally maintained in raised position, as illustrated in Fig. 2, by the mercury m in the pot 50, it being noted that the interior of the pot communicates with the cylinder 54 through openings 60 at the bottom thereof. Steam is admitted to the top of the mercury pot F under static pressure through a nipple 61 entering its side and connected with a steam supply pipe to be later described. Steam under velocity pressure is admitted to the top of the cylinder 54, in which the piston 55 slides, through a port 62 into which is threaded a pipe 63 connected by a pipe 64 leading directly from the Pitot tube to be later described.

Piston counterweight.—For counterweighting the piston 55 and its attached parts I preferably employ a bell-crank lever 70 fulcrumed at 71 on a bearing extending from the side of the casing C. The short arm of the bell-crank 70 carries a pendant rod 72 having means at its lower end for supporting a plurality of weights 73 which may be subtracted or added to as required. The long arm of the bell-crank 70 terminates in a fork having slots 74 engaged by a cross-pin 75 driven through the upper piston rod 56. As the bell-crank 70 is rocked under the rise and fall of the piston 55 the leverage of its shorter arm will be varied to adjust the effect of the weights 73 in proportion as required to counterbalance the piston and its parts under varying operating conditions, this action being more fully described hereinafter. The lower piston-rod 57 is con-

nected to the steam-pressure operated piston 26 through a differential compensating-mechanism or governor constructed and arranged as next described.

5 *Differential governor.*—Between the static steam-pressure control-member or piston 26 and the velocity steam-pressure control-element or piston 55 is a differential mechanism which constitutes the main governing element of the apparatus. One form of this governor is illustrated in Fig. 2 and shown in detail in Figs. 5 to 7. As here illustrated the upper end of the piston 26, which is operated from the steam pressure cylinder 40, 10 is reduced in diameter to receive a flanged cup 80 fastened thereto by a cross-pin 81. The lower end of the piston-rod 57, operated from the piston 55, is also reduced in diameter to receive a similarly-shaped inverted cup 82 held thereon by a cross-pin 83. 15 Suspended from the upper cup 82 is a differential weight W which is constituted by a series of semicircular weight-links 85 joined together by a novel arrangement of 20 mechanism as next described. As shown in Figs. 5 and 6, the weights 85 consist of half-rings which are pivoted together by means of wire pins 86 passing through hinge-lugs 87 and bent around at their ends to hold 25 them in place. Each half-ring or weight-link 85 is provided with a forwardly projecting lug 88 on its inner edge adjacent the joint which it makes with its complementary link, see the enlarged sectional view, Fig. 7. 30 The lugs 88 on each two opposite link-sections or half-rings are adapted to engage on opposite sides of a wire-staple 89 which has its ends secured loosely in the opposite complementary links. The upper link of 35 the series is fastened to the bottom of the upper cup 82 by means of screws 90, see Fig. 5, and the distance between the cups is so proportioned that the lower link of the series will normally be suspended just above the 40 bottom cup 80, see Fig. 2. All of the links will therefore be normally supported from the upper cup, due to the fact that the play or swiveling action at their hinges is limited by the dogging action of the lugs 88 on the 45 cross wires or staples 89. In other words, the lugs 88 on each pair of links 85 pinch against the staple 89 and prevent the links from being extended in the axial direction of the chain or helix formed by the series of 50 connected links, see Figs. 6 and 7. When, however, the lower cup 80 rises in relation to the upper cup 82 the individual links are successively picked up and the weight of each added to the lower cup while the remaining links hang suspended from the upper cup, the functioning of this mechanism being explained more fully in connection with the operation of the complete apparatus.

65 *Alternative form of differential gov-*

ernor.—A modified form of the differential governing-device is illustrated in Fig. 3 of the drawings, in which a single cylindrical weight 95 is carried by the piston 26 and normally held submerged in a bath of mercury contained in a jar 96 suspended from the lower piston-rod 57 of the piston 55. The rising of the piston 26, or the dropping of the piston 55, alters the degree of submergence of the weight 95 in the mercury m and thus varies its operative effect on the piston 26 in accordance with requirements. For this purpose the piston-rod 57 has an enlarged extension 97 at its lower end carrying an inverted cup 98, to which is attached 70 a cylindrical casing 99. The lower part of this casing 99 is formed with a flange 100, to which is attached the mercury jar 96 by means of an inturned flange 101 at its top 75 held by screws 102.

The upper part of the jar 96 is formed with a saucer-like rim 103 which provides an enlarged basin to add volume to the body of mercury contained in the jar. This construction provides that as the weight 95 rises 80 out of the mercury m there will be a minimum change in the level of the fluid. Extending upwardly from the bottom of the jar 96 above the level of the mercury contained therein is a cylindrical sleeve 104 85 having a central bore through which the piston 26 slides with a loose fit. The upper end of the piston 26 is reduced in diameter to adapt it to slide into an axial bore 105 in the piston-rod 57, it being noted that 90 holes 107 are drilled through the rod 57 into its bore 105 to allow the escape of air so that the movement of the piston 26 therein will not be resisted. The weight 95 is attached to the piston 26 by means of a flanged 95 collar or cup 108. As shown in Fig. 3, the weight is fastened to the flange by means of 100 screws 109, and the collar or cup 108 is secured to the piston 26 by a cross-pin 110. It will be seen that the weight 95 is free to 105 slide up and down within the mercury jar 96 without contact with the sides thereof or with the bushing 104, and the casing 99 is formed with openings 112 to permit the 110 egress of air so as not to resist the movement 115 of the weight. The function of this modified form of differential compensating-device is the same as that previously described in which the connected weights are employed, its method of operation being hereinafter more fully explained.

The pressure connections.—For the static pressure and velocity head control of the piston 55 I may employ a usual type of Pitot tube device as illustrated in Figs. 8 125 and 9. In these views the main steam pipe 115 leading from the boiler is shown in section with the arrow a indicating the direction of flow therethrough. A nipple 116 is inserted through the side of the pipe 115 130

with a hand-valve 119 connecting it to a steam pipe 117. Spaced away from the nipple 116 is a second nipple having an upwardly projecting pipe 120 with a bent end 5 opening toward the direction of flow of steam in the pipe 115. This is a conventional form of Pitot tube as generally used for measuring the velocity head or flow of the steam. On the nipple 118 is a hand-valve 10 121 which connects with a steam pipe 122. Referring now to Figs. 1 and 2, the pipe 117 for the static pressure leads through the top of the casing C down the side thereof, and is provided with a T 123 which connects 15 with the nipple 61 leading into the top of the mercury pot F to supply pressure through the mercury to the under side of the piston 55. The steam pipe 117 is continued downwardly, as indicated at 124, to supply static pressure to the cylinder P, a suitable fitting 125 at its lower end being connected 20 to the nipple 43 leading through the pedestal 41 to the bottom of the cylinder 40. The steam pipe 117, 124 is continued horizontally 25 across the bottom of the casing C and connected to the motor M by means of suitable fittings 126, 127 and 128, the latter a nipple leading into the steam-chest 14 on the side of the motor cylinder 2. The connections 30 above described supply static pressure to the several steam cylinders; while the steam pipe 122 leads down through the top of the casing C and by means of an elbow 130 connecting with the nipple enters the duct 62 35 in the cylinder 50, thus providing a velocity head acting against the top of the piston 55.

It will be understood that the steam connections may be varied as desired, and a modified form of steam flow device employed in place of the Pitot tube. For example, in Fig. 10 I have illustrated a modern type of orifice plate, sometimes called a "Mexican hat." With this arrangement the main steam pipe 115 leading from the boiler is formed in two flanged sections 135, 136, with the orifice plate 137 held between the flanges thereof. With this construction a nipple 138 connects through valve 139 and pipe 140 with the velocity side of mercury pot F and a second nipple 141, valve 142 and pipe 143 connects with the static side of the mercury pot.

Combustion controls.—In the general view in Fig. 1 is shown an arrangement of 55 my improved apparatus for regulating combustion in a conventional type of steam boiler furnace. It is to be understood, however, that this showing is by way of example only, as the apparatus is adapted for use with other types of furnaces and with different methods of control. In Fig. 1, B designates the boiler having its furnace fed by an automatic stoker S which is operated by a steam engine E taking pressure from the boiler through connections not herein

illustrated and controlled by a valve 145. The valve lever 146 is weighted to normally hold it closed and is adapted to be opened by means of a cord or chain 147 passing over a pulley 148. A larger pulley 149 fast 70 with the pulley 148 has a chain 150 leading therefrom over a third pulley 151, and thence down to the main operating motor piston-rod 5 to which it is connected at 152.

The over fire or induced draft in the combustion chamber of the furnace is controlled by means of a damper D in the main flue H. The damper D is moved from a lever 155 carrying a weight 156 at one end which tends to hold it closed. Connected to the 80 opposite end of the lever 155 is a cord or chain 157 which forms a continuation of the chain 150 fastened to the piston-rod 5. Through this arrangement the dropping of the piston 4 will cause its rod 5 to open the 85 damper D.

In Fig. 1 I have also illustrated the furnace as provided with a forced draft under the fire which is fed from a suitable blower or fan indicated at J as being operated from a steam turbine K. Pressure is supplied to the turbine motor K through a steam pipe 160 leading from the boiler and in which is a control valve 161. The valve 161 is operated from a weight-lever 162, the weight 95 tending to maintain the valve closed. Fastened to the outer end of the lever 162 is a cord or chain 163 leading up over a pulley 164. The pulley 164 is fast with a larger pulley 165 which has a chain leading there-over and connected to the chain 150 fastened to the piston-rod 5. It will thus be seen that both the over-fire and under-fire drafts and the fuel feed are controlled from the movement of the piston 5, and other controls may be added when required. In place of the steam engines employed to operate the stoker S and the forced draft fan J, I may employ electric motors having suitable switches and rheostats for regulating 110 the current through the operation of controls from my improved apparatus. In other cases, where liquid fuel is used in the furnace, the supply to the burner nozzles may be controlled by valves operated from the 115 apparatus through suitable connection with the piston-rod 5. The method of operation of the complete device is as follows.

Method of operation.—In Fig. 2 the several units of the apparatus are illustrated 120 in convenient position to render the showing clear without regard for their normal cooperative relation when the device is in use. The individual elements of the mechanism may be proportioned and adjusted in 125 correlation in accordance with requirements for different types of boilers, varying conditions of operation, and different methods of control. For the purpose of the present explanation, however, we may assume a typ- 130

ical condition. For example, assuming that the boiler is to operate at say 124 pounds gauge pressure, and that the constant weight 45 on the piston 26 is proportioned to resist 5 120 pounds pressure in the cylinder 40, then with the boiler at anything over 120 pounds the weight will be lifted off its seat on the pedestal 41. Assuming further, that each 10 of the half circular weights 85 of the differential weight-mechanism W is proportioned to resist a half pound of pressure in the cylinder 40, then with a static pressure in the boiler of 124 pounds the pressure supplied from the main steam pipe 115 through 15 pipes 117 and 124 to bottom of cylinder 40 will cause the piston 26 to raise the weight 45 until it is balanced by eight of the one-half pound weights 85; it being understood that as the piston 26 rises the cup 80 on its 20 upper end successively picks up the differential weights 85 to increase the operative force of the weight 45. As the piston 26 rises it lifts the long arm of lever 25 of the valve-gear V and slides the valve 10 to 25 open the lower port 13 in the steam-chest 14, thus admitting steam to the bottom of the cylinder 2 beneath the piston 4. The pressure on the under side of piston 4 raises the latter to slide its rod 5 upwardly and by 30 means of the chains connected to the rod operates the control for the furnace as follows:

Referring now to Fig. 1, as the piston-rod 5 slides upwardly the chain 150 is paid out 35 over the pulleys 151, 165 and 149 with the following result: First, the flue-damper D is caused to be rocked into partly closed position under the action of its weight 156; second, the valve-lever 146 is lowered to reduce 40 the pressure to the engine E operating the automatic-stoker S; and third, the lever 162 is also lowered to reduce the pressure supplied through valve 161 to turbine K which operates the forced draft fan or 45 blower J.

It may be assumed that with the controls in position as shown in Fig. 1 the boiler is operating under normal pressure with the constant weight 45 and added differential 50 weights 85 in the cup 80 balancing the 124 pounds pressure in the cylinder 40. To maintain this condition, however, the piston 4 must be balanced and this is accomplished through the action of the valve-gear V. As 55 the piston 4 rises its rod 5 lifts the long arm of lever 32, the short arm of which, operating through the reach-rod 30, depresses the fulcrum of lever 25, and in this way the valve 10 is moved back into position to 60 maintain the piston 4 balanced in the position it has previously assumed. Should the pressure in the boiler continue to rise, however, the continued upward movement of the piston 26 will maintain the valve 10 open 65 to admit steam to the under side of piston

4 to slide its rod 5 upwardly until all of the controls, i. e., the flue damper D and valves 145 and 161, are entirely closed.

Considering the boiler as operating at normal, should the pressure therein start to drop, for instance, from lowered combustion in the furnace, the differential weights 85 acting in conjunction with the constant weight 45 will cause the piston 26 to descend under the lessened pressure in the cylinder 40. This action will unseat the valve 10 to admit steam at the top of cylinder 2 so that the pressure will carry the piston 4 downwardly, thus causing its rod 5 to pull the chain 150 to open the controls to increase 80 combustion in the furnace.

The above explanation of the operation of the device takes into consideration only its action under control of static pressure, but indicates the general method of functioning 85 of the control actuator or motor M and its valve-regulating means as constituted by the weight-controlled or differentially balanced pressure piston 26. Combustion control devices operated under static pressure have 90 heretofore been employed in the art, but have not been found satisfactory and sufficient for the purpose intended because of their sluggish action. Slight changes in the condition of the fire may not be immediately reflected in the boiler pressure and hence the controls will not be operated promptly enough to increase combustion before the pressure has fallen to a considerable extent. Moreover, a sudden overload on the 100 boiler, as resulting from the starting of an additional unit of machinery, will not immediately reduce the static pressure in the boiler and hence the drain may be continued until it is too late to check the fall by opening the controls to increase combustion. For these and other reasons it is therefore desirable to provide means for actuating the controls under fluctuations in the steam flow or velocity head, which means will be more 105 quickly responsive to an increase in the load on the boiler. The present invention embraces such an improved control of combustion under changes in steam flow or velocity head as effected by certain elements of the 110 apparatus above described, the novel method of operation of which is as follows:

Operation under velocity head control.—Assuming that the boiler is running along at normal gauge pressure of 124 pounds, 115 with the parts of the control apparatus in balanced relation as above described, if a new unit of machinery is started a heavy load is placed on the engine with a sudden heavy demand for steam from the boiler. The increased demand for steam from the boiler will instantly cause an increased velocity head 120 in the steam main, which acting through the Pitot tube device or aperture plate and connections to induce pressure on the piston 55 125

in the mercury pot F will cause an immediate response of the apparatus to actuate the combustion controls. That is to say, an increase in velocity head in the steam main 5 increases the pressure through Pitot tube 120, see Fig. 8, and steam pipe 122 leading to the top of piston 55 in the mercury pot F, and meanwhile the static pressure through pipe 117 to the mercury in the pot will be lowered. The increase in pressure on the top 10 of piston 55 will therefore overcome its balance and force the piston downward, causing its rod 57 to progressively deposit the differential weights 85 on the cup 80 surmounting the piston 26. The piston 26 will thus be overbalanced and forced downwardly against the pressure in the cylinder 40, and during its motion it will shift the lever 25 to slide the valve 10 to admit pressure at 20 the top of the motor cylinder 2. Consequently, the piston 4 will be caused to descend to slide its rod 5 to pull the connecting chain 150, see Fig. 1, whereby to open the damper D and also the control-valves 25 145 and 161 for the stoker engine E and blower turbine K. Through this action combustion in the furnace is immediately increased until pressure in the boiler is raised to take care of the extra load. As the pressure 30 in the boiler increases the piston 26 will be raised again, and acting through the lever 25 it will operate the valve-gear V to balance the piston 4 in proper position to once more set the controls for normal combustion 35 in the furnace without waste of fuel.

As the piston 55 descends it rocks the bell-crank lever 70 connected to its rod 56 to raise the counterweights 73, and as the bell-crank turns on its pivot 71 the leverage of 40 its short arm diminishes to reduce the operative force of the weights. The bell-crank 70 and its weights 73 are so proportioned that as the differential weights 85 are dropped from piston 55 into the lower cup 80 on 45 the piston 26 the loss of weight on the piston 55 is compensated, or substantially so, by the decreasing effect of the weights 73 on the bell-crank 70 during its rocking motion. In this way the piston 55 and its connected parts are at all times maintained under an approximate balance so that it will be more sensitive to the control of pressure 50 from the Pitot tube.

It has been explained that the leads from 55 the static and flow sides of the aperture plate 137 in the main steam pipe 115, see Fig. 10, control the pressure on the piston 55 in the mercury pot F in the same manner to obtain the same result as with the Pitot tube shown 60 in Figs. 1 and 8. It is also to be understood that the modified form of differential-weight device shown in Fig. 3, which is the preferred form of this element, functions in substantially the same manner as the linked weights 65 85 illustrated at W in Fig. 2. When the

piston 55 is forced down in the mercury pot F the mercury jar 96 will be lowered to lessen the degree of submergence of the cylindrical weight 95 on the lower piston 26. The operative force of weight 95 on piston 70 26 is therefore augmented to cause the piston to be overbalanced against the pressure in the cylinder 40, whereby the piston will drop to operate the valve 10 in the manner and for the purpose as previously explained. 75

It will be observed from the foregoing explanation that my improved control-device is caused to act practically instantaneously upon any change in velocity head in the steam main, and hence the operation of the 80 combustion controls is much more prompt than where fluctuations in static pressure alone are depended upon to initiate the operation of the controls. It will also be seen that the present device is not only more sensitive in action, but also more accurate and efficient in its control so that conditions of combustion in the furnace are not permitted to vary between wide extremes. In other words, the device operates automatically to 90 increase combustion in accordance with requirements of the load on the boiler or the steam flow therefrom, but not to an extent to cause waste of fuel by allowing the pressure to get too low and then increasing combustion 95 to an abnormal degree.

While I have described and illustrated my invention as embodied in apparatus of a certain structure, it is to be understood that changes may be made in the form and arrangement of its parts beyond the modifications herein suggested, and such alterations in design and construction would fall within the scope and spirit of the invention as defined by the appended claims. 100

I claim:

1. In a combustion-controlling device for steam boiler furnaces, the combination of a pressure operated motor for adjusting the furnace controls, a balanced piston operative 110 under static pressure from the boiler on one side and velocity pressure on the opposite side, a differential governor operated from the balanced piston, and means operated by the movement of said piston and controlled 115 by the action of the governor to control the pressure in the motor to regulate its adjustment of the furnace controls.

2. In a device of the type specified, the combination with the controls of a steam 120 boiler furnace, of a motor for operating said controls, a piston displaceable by steam pressure from the boiler under velocity head, a differential governor connected to said piston, and means actuated by said piston 125 under the control of the governor to regulate the action of the motor to operate the controls in accordance with the fluctuations in steam flow from the boiler.

3. In a device of the type specified, the 130

- combination of a motor for operating the controls of a steam boiler furnace, means to energize the motor to open and close the controls, a balanced piston displaceable by pressure under velocity head from the boiler, a differential governor connected to said piston, and means operated by the piston under the control of the governor to regulate the application of energy to the motor.
- 10 4. In a device of the type specified, the combination of a piston for operating the controls of a steam boiler furnace, means for supplying pressure to the piston to move it in opposite directions to open and close the controls, a second balanced piston, a differential governor between the first and second pistons, means to supply pressure under velocity head from the boiler to the balanced piston, and means operated by the displacement of the balanced piston and acting through the differential governor to regulate the action of the control-operating piston.
- 15 5. In a device of the type specified, the combination of a piston for operating the controls of a steam boiler furnace, means for applying pressure on opposite sides of the piston, a valve for controlling the direction of application of pressure on the piston, a second balanced piston, a differential gravity operated governor connected to the balanced piston, means for applying pressure under velocity head from the boiler to displace the balanced piston, and means operated by the movement of the balanced piston and controlled by the governor to regulate the action of the valve for the control-operating piston.
- 20 6. In a device of the type specified, the combination of a piston for operating the controls of a steam boiler furnace, a valve for admitting pressure to opposite sides of said piston, a second piston operated by static pressure from the boiler to shift the valve to admit pressure to the first piston to operate the furnace controls, a valve-gear operated from the first piston to reset the valve to hold said piston in balanced position, a third piston operated by steam pressure under velocity head from the boiler, and means operated from the third piston to regulate the movement of the second piston which controls the valve for the first piston.
- 25 7. In a device of the type specified, the combination of a piston for operating the controls of a steam boiler furnace, a valve for admitting pressure to opposite sides of said piston, a second piston operated by static pressure from the boiler to shift the valve to admit pressure to the first piston to operate the furnace controls, a valve-gear operated from the first piston to reset the valve to hold said piston in balanced position, a third piston operated by steam pressure under velocity head from the boiler,
- and differential mechanism operated from the third piston to resist the movement of the second piston after the latter has shifted the valve for the first piston to a predetermined extent.
- 30 8. In a device of the type specified, the combination of a fluid pressure piston for operating the controls of a steam boiler furnace, a valve for admitting pressure to opposite sides of said piston, a second piston operated under static pressure from the boiler to shift the valve for the first piston, a counterweight for resisting the movement of the second piston, a third piston operated by pressure under velocity head from the boiler, and a differential governor-mechanism acting to automatically increase and decrease the force of the weight for resisting the movement of the second piston in accordance with fluctuations in steam flow from the boiler.
- 35 9. In a device of the type specified, the combination of a motor for shifting the furnace controls, means for controlling the direction of action of the motor, a piston operated by static pressure from the boiler to operate the motor-controlling means, a weight acting against said piston, a balanced piston operated by pressure under velocity head from the boiler, and differential mechanism operated by the movement of the balanced piston to increase and decrease the weight on the static pressure piston whereby to regulate its control of the motor under fluctuations in steam flow from the boiler.
- 40 10. In a device of the type specified, the combination of a fluid pressure cylinder, a piston in said cylinder, means for connecting said piston to shift the furnace controls, a valve for admitting pressure to opposite sides of said piston, a second piston operated by static pressure from the boiler, a counterweight on the static piston, means connecting the static piston to operate the control-valve for the first piston, a third piston operated by pressure under velocity head from the boiler, and a differential-governor operated from the third piston to apply a variable degree of weight on the static-piston to regulate the action of the latter in proportion to the increased steam flow from the boiler.
- 45 11. In a device of the type specified, the combination of a motor for shifting the furnace controls, means for controlling the direction of action of said motor, a piston operated by static pressure from the boiler to actuate the motor-controlling means, a second piston operated by pressure from the boiler under velocity head, a mercury jar carried by the second piston to adapt it to be raised and lowered by the movement of said piston, and a weight on the first piston submerged in the mercury in the jar carried by the second piston whereby movement of

the second piston regulates the degree of submergence of said weight to vary its operative force on the first piston.

12. In a device of the type specified, the combination of a motor for shifting the furnace controls, means for controlling the direction of action of said motor, a piston operated by static pressure from the boiler to shift the motor-controlling means, a second piston operated by pressure under velocity head from the boiler, a mercury jar suspended from the second piston and provided with a sleeve through which the first piston slides, and a cylindrical weight supported from the first piston within the mercury jar to adapt it to be submerged in the mercury to a varying degree in accordance with the relative displacement of the first and second pistons.

20 13. In a device of the type specified, the combination of means for shifting the furnace controls, a piston operated under static pressure from the boiler to regulate the action of said control-operating means, a second balanced piston operated by pressure from the boiler under velocity head, a mercury jar suspended from the balanced piston and provided with an opening in its bottom through which the static piston slides, and a cylindrical weight surrounding the static piston and carried thereby to adapt it to be submerged to a variable extent in the mercury in the jar carried by the balanced piston in accordance with the relative displacement of said pistons.

40 14. In a device of the type specified, the combination with the furnace controls, of a motor for operating said controls, means for controlling the operation of said motor, a mercury pot, a piston maintained suspended by the mercury in said pot, means for admitting static pressure from the boiler to hold the piston suspended, means for admitting pressure under velocity head from the boiler to act against the opposite side of the piston, and means operated from the movement of said piston to regulate the action of the motor-controlling means in accordance with variations in the flow of steam from the boiler.

50 15. In a combustion-controlling device for steam boiler furnaces, the combination with the furnace controls, of a fluid pressure cylinder, a piston slidable in said cylinder and connected to operate the furnace controls, a valve in the cylinder for controlling the admission of pressure to opposite sides of the piston, a lever for shifting said valve, a second lever operated from the piston and connected to the first lever to shift the fulcrum of the latter to re-seat the valve, a second piston operated by static pressure

from the boiler and connected to shift the valve lever, a third piston operated by pressure under velocity head from the boiler, 65 and means between the third piston and second piston for counterbalancing the second piston to overcome the static pressure thereon.

16. In a combustion-controlling device for 70 steam boiler furnaces, the combination of a chamber containing mercury, a piston suspended in the mercury in the chamber, means for admitting steam under static pressure to the chamber on one side of the piston, and means for admitting steam under velocity pressure to the chamber on the opposite side of the piston whereby to operate the latter in the manner and for the purpose substantially as described.

80 17. In a combustion-controlling device for steam boiler furnaces, the combination of a cylinder containing a heavy fluid, a piston suspended in the fluid in the cylinder, means for admitting steam under static pressure to the cylinder on one side of the piston, and means for admitting steam under velocity pressure to the cylinder on the opposite side of the piston.

85 18. In a combustion-controlling device for steam boiler furnaces, the combination of a cylinder containing mercury, a piston slidable in said cylinder, and means for supplying steam under velocity head to the interior of the cylinder to act against the mercury to control the position of the piston in the cylinder.

90 19. In a combustion-controlling device for steam boiler furnaces, the combination of a cylinder, a piston slidable in the cylinder, a 100 chamber communicating with the cylinder, a supply of heavy fluid in the chamber for maintaining the piston suspended in the cylinder, means for admitting steam under velocity pressure to the chamber to act 105 through the fluid on one side of the piston, and means for admitting steam under static pressure to the cylinder to act on the opposite side of the piston.

110 20. In a device of the type specified, the combination of a cylinder, a piston slidable in said cylinder, a chamber surrounding the cylinder and communicating therewith at one end thereof, a quantity of mercury in the chamber maintained at the same level in the 115 cylinder, means for supplying steam to the chamber under velocity pressure to act through the mercury on one side of the piston, and means for supplying steam to the cylinder under static pressure to act against 120 the opposite side of the piston.

In testimony whereof I affix my signature.

WILLIAM H. LARKIN, Jr.
